UNITED STATES PATENT OFFICE.

CHARLES B. KING, OF DETROIT, MICHIGAN, ASSIGNOR TO NORTHERN MOTOR CAR COMPANY, OF DETROIT, MICHIGAN, A CORPORATION OF MICHIGAN.

CLUTCH.

No. 877,437.

Specification of Letters Patent.

Patented Jan. 21, 1908.

Application filed April 3, 1905. Serial No. 253,586.

To all whom it may concern:

Be it known that I, CHARLES B. KING, a citizen of the United States, residing at Detroit, county of Wayne, State of Michigan, have invented a certain new and useful Improvement in Clutches, and declare the following to be a full, clear, and exact description of the same, such as will enable others skilled in the art to which it pertains to make and use the same, reference being had to the accompanying drawings, which form a part of this specification.

My invention relates to clutches, and the object of my improvements is to provide an improved clutch mechanism and one in which the operative parts of a motor and transmission mechanism may be connected and disconnected.

In the drawings:—Figure 1, is an elevation 20 of a gas engine and transmission mechanism embodying my invention. Fig. 2, is a detail sectional view of the valve H¹. Fig. 3, is a sectional view of the main shaft of the engine, the fly-wheel and some adjacent parts. Fig. 4, is a perspective view of the disk G³ and sleeve G⁶.

A, A, are the cylinders; B, is the crank case and C, the fly-wheel.

E, is the main shaft of the engine.

I form an aperture H through the cylinder and provide a pipe H² leading therefrom. The aperture H may be below the upper end of the piston stroke or it may be in the explosion chamber.

H¹, is a non-return valve in the pipe H² and opening outward. The pipe H² communicates with a reservoir H³. When the engine is working, there is a considerable pressure in the cylinder and the gases therefore pass through said opening past the valve H¹ into the pipe H² and accumulate and cause a pressure in the tank H³. The degree of such pressure may be regulated by the position of the opening H.

Through the main shaft E, is formed a passage e, which extends from end to end of the crank shaft and through the cranks.

F, are fan blades in the fly-wheel C. Within the fly-wheel and supported coaxially therewith by said fan-blades is a cylinder G closed at its inner end. The passage e communicates with the interior of the cylinder G through a passage at the center of its closed end.

G², is a diaphragm preferably of leather,

its periphery resting upon an annular shoulder within the cylinder G.

G¹, is a collar fitting within the cylinder G, its inner edge coming against the periphery of the diaphragm G² and holding it in place against the annular shoulder in said cylinder. The inner edge of the collar G¹ is preferably provided with a bead g. The outer edge of the collar G¹ is turned over and secured by screws g⁴ extending into the edge of the wall of the cylinder G and serving to secure, and draw said collar tight against the edge of the diaphragm G². From the collar G¹, a flange G⁴ extends inward and then outward to form a sleeve G^{4a}.

g², is a leather annulus secured to the inner face of the flange G⁴.

G³, is a metal disk within the cylinder G between the diaphragm G² and the flange G⁴.

G⁵, is a shaft to which the power of the engine is to be transmitted.

G⁶, is a sleeve surrounding the shaft G⁵.

g⁶, are longitudinal slots extending into the inner wall of the sleeve G⁶.

g⁷, are pins extending from the shaft G⁵ into the slots g⁶. The sleeve G⁶ is rigidly connected to the disk G³.

g⁵, is a bushing between the sleeves G^{4a} and G⁵.

H⁴, is a pipe leading from the reservoir H³.

H⁵, is a multiple way valve in the pipe H⁴, by which air from the reservoir H³ may be led into the passage e and thence to the cylinder G, or may be exhausted from said passage and cylinder to the open air or may be led to a brake operating cylinder H⁶ and exhausted therefrom.

h⁵, is a handle by which the valve H⁵ may be manipulated.

H⁶, is a pipe communicating with the pipe H⁴ at one end bending upward and communicating with a pipe H⁸, which passes through a stuffing box in the end of the crank shaft and communicates with the passage e through the crank shaft E.

H⁷, is a set screw by which the pipe H⁸ is secured in position.

By turning the handle h⁵, so as to allow a free passage through the pipe H⁴, compressed air or gases is caused to pass through the passage e into the cylinder G pressing the disk G³ against the flange G⁴ and therefore binding the sleeve G⁶ and shaft G⁵ to the shaft E. By turning the handle h⁵ so as to cause the pipe H⁴ beyond the valve H⁵ to communicate

with the outer air, the compressed gases are discharged from the cylinder G through the passage e, releasing the connection between shafts G⁵ and E.

5. What I claim is:—

1. In a clutch mechanism, the combination of a cylinder having one end closed, a flange fixed to the edge of said cylinder around its open end and extending part way 10 to the center, a disk in said cylinder between said flange and the end of said cylinder, means for connecting said disk toward its center with the transmission mechanism, and means for supplying fluid under pressure to 15 said cylinder back of said disk to press it against said flange to bind said disk and flange together for the purpose described.
2. In a clutch mechanism, the combination 20 of a cylinder having one end closed, a flange fixed to said cylinder at the edge surrounding its open end and extending part-way to the center, the said flange being provided with an annular coaxial outwardly extending sleeve, a disk in said cylinder between 25 said flange and the end of the cylinder, said disk being provided with a central projection extending beyond said flange in said sleeve, and means for supplying fluid under 30 pressure to said cylinder back of said disk to press it against said flange for the purpose described.

3. In a clutch mechanism, the combination 35 of a cylinder having one end closed, a flange fixed to said cylinder, a disk in said cylinder between said flange and the end of said cylinder, said disk being provided with a central projection extending beyond said flange, said projection being provided with a central longitudinal aperture, and a longitudinal slot in its wall, a shaft projecting into 40 said central aperture provided with a lug extending into said slot, and means for supplying fluid under pressure to said cylinder back of said disk to press it against said flange for 45 the purpose described.

4. In a clutch mechanism, the combination 50 of a cylinder having one end closed, a flange fixed to said cylinder provided with an

annular coaxial outwardly extending sleeve, a disk in said cylinder between said flange 55 and the end of the cylinder, said disk being provided with a central projection extending beyond said flange in said sleeve, said projection being provided with a central aperture and a longitudinal slot in its wall, a shaft 60 extending into said aperture and provided with a lug extending into said slot, and means for supplying fluid under pressure to said cylinder back of said disk to press it against said flange for the purpose described. 65

5. In a clutch mechanism, the combination 70 of a cylinder having one end closed, a flange fixed to said cylinder, a disk in said cylinder between said flange and the end of said cylinder, means for supplying fluid under pressure to said cylinder back of said disk to press it against said flange, and a shaft, said disk being connected to said shaft so as to restrain relative rotary motion between said disk and shaft and to permit a motion of said disk in the direction of the length of said shaft.

6. In a clutch mechanism, the combination 75 of a cylinder having one end closed, a flange fixed to said cylinder at its edge around its opened end, a disk in said cylinder between said flange and the end of said cylinder, means for supplying fluid under pressure to said cylinder back of said disk to press it against said flange to bind said cylinder and disk together, and a transmission mechanism, said disk being connected towards its center adjacent to the open end of said cylinder with the transmission mechanism so as to restrain relative rotary motion between said 80 disk and transmission mechanism and to permit a motion of said disk relative to said cylinder in the direction of the axis of said cylinder, for the purpose described.

In testimony whereof, I sign this specification in the presence of two witnesses.

CHARLES B. KING.
